Primary Examiner — Elizabeth Albert*Assistant Examiner* — Kelley Donnelly(74) *Attorney, Agent, or Firm* — Keisling & Pieper PLC;
Stephen D. Schrantz(57) **CLAIM**

The ornamental design for a leaning stand, as shown and described.

DESCRIPTION

FIG. 1 is an isometric view of a leaning stand showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a front view thereof showing extrusions in a folded position;

FIG. 8 is a left side view thereof showing extrusions in a folded position; and,

FIG. 9 is a left side view thereof, shown in a fully folded position.

The broken lines showing is included for the purpose of illustrating environment and forms no part of the claimed design.
